UNITED STATES PATENT OFFICE.

JOHN A. SMITMANS, OF PITTSBURG, PENNSYLVANIA.

ASH-EXTRACTOR FOR GAS-PRODUCERS.

No. 892,767.

Specification of Letters Patent.

Patented July 7, 1908.

Application filed November 5, 1907. Serial No. 400,775.

To all whom it may concern:

Be it known that I, JOHN A. SMITMANS, a resident of Pittsburg, in the county of Allegheny and State of Pennsylvania, have 5 invented certain new and useful Improvements in Ash-Extractors for Gas-Producers, of which the following is a specification.

This invention relates to gas producers and has particular reference to the means employed for removing the ashes and cinders 10 from the ash hopper.

The invention is embodied in a horizontally movable extractor, preferably though not necessarily rotatable, and the primary 15 object is to provide for a certain and positive displacement of the ashes, the action being such as to thoroughly separate the ashes from the body of fuel contained in the fuel chamber. This is accomplished by holding 20 the material above the extractor from moving with the latter, with the result that as the ashes work down they are displaced and caused to drop into the ash pit.

In the rotatable form of extractor here 25 shown, an important feature is the relative arrangement and inclination of the coöperating ribs or blades of the fixed and movable portions of the mechanism.

In the accompanying drawings, Figure 1 is 30 a vertical sectional view of the improved producer. Fig. 2 is an inverted plan view of the ash hopper. Fig. 3 is an inverted plan view of the ash extractor mechanism. Fig. 4 is a developed section of the ribs of the ash 35 hopper and the blades of the extractor, taken on line 4—4 of Fig. 3. Fig. 5 is a detail view of the water-cooled extremity of the blast pipe. Fig. 6 illustrates the improved ash 40 hopper and extractor adapted to a blast pipe entering the lower end of the producer.

Referring to the drawings, the side walls 2 of the producer body are supported on posts 3 above the water pit 4, the lower portion of the ash hopper 5 being submerged in the 45 water in the usual manner. Leading from the upper portion of the producer body is the gas out-take 9. The body is closed at the top by the hollow water-jacket structure 6, having the depending annular wall 7 which incloses the coal or other fuel magazine 8, while outside of this depending wall is the 50 gas space 9'. The top structure 6 is raised centrally at 10 and enlarged to form the fuel hopper 11 which is closed by the vertically 55 movable bell 12. Extending through a central passageway in the bell is the blast pipe

13 which is sustained and may be raised and lowered as required by chains 14, passing to any suitable lifting and supporting mechanism, not shown. The bell may be similarly 60 raised and lowered by chains 15 without disturbing the blast pipe, the vertically movable water seal 16 being arranged between the bell and the blast pipe to prevent the escape of gas without interfering with the 65 movement of either part with relation to the other. The upper end of pipe 13 has telescoping connection with the blast supply pipe 17, through which air alone or air mixed with gas or steam may be introduced, the 70 vertically movable water seal 18 preventing gas from escaping at the juncture of the pipes. Steam generated in the water-jacket of top structure 6 may be utilized in the blast, being conducted thereto through pipe 75 19. For coarse fuel through which the blast may easily pass, the position of the lower or discharge end of the blast pipe is comparatively low to avoid the formation of too great a percentage of CO₂ gas, and from such 80 position is raised according to the fineness of the fuel.

It will be understood that the lower end of the blast pipe is embedded in the fuel being consumed, and to protect the same it is provided with the flaring or mouth-like ring 20 which is hollow for the circulation of water, with the water-circulating pipes 21 and 22 connected thereto and leading upward through pipe 13. In side walls 2 are the 90 usual poke holes 23 closed by plugs 24.

Ash hopper 5 is open vertically save for the central cone 25, from which radiate horizontal ribs 26 to the annular wall of the hopper. Instead of being disposed vertically, the ribs 95 are preferably tipped or inclined laterally to present the sloping faces 26' to the ashes and cinders and over which faces the latter readily pass in their descent.

Rotatable beneath the ribbed lower portion of the ash hopper is the circular and rotatable extractor which consists of an outer ring 27 and the inner ring 28, with a series of blades 29 between and secured to the rings. These blades are preferably inclined in parallel planes and so spaced apart that the lower portion of each blade underlaps the upper portion of the next blade, being at the same time spaced vertically therefrom, as clearly shown in Fig. 4, thus forming the diagonal 100 ash passages 29'. The distance between the top edges of adjacent blades 29 is preferably 105 110

the same as the distances between the lower edges of adjacent bars 26. The rotation of the extractor causes the ashes and cinders to flow downward through diagonal passages 5 29' and discharge over the lower edges of the blades, the action being suggestive of the blades of a fan or blower, or of the blades of a turbine. The ashes thus discharged into pit 5 slide down the inclined 10 bottom of the latter and away from beneath the producer, as will be understood. To facilitate the clearing of the coarse ashes or clinkers, the lower edges of blades 26 are serrated or of toothed formation, as indicated at 30, while the upper edges of blades 29 are similarly formed at 31, the action of these toothed edges being to grind or crush any cinders which might otherwise obstruct the extractor.

20 The invention is not limited to any particular number or even to a plurality of ribs 26 in the hopper and blades 28 in the extractor. The primary function of blades 26 is to prevent the body of ashes within the 25 hopper from rotating with the extractor, and it is obvious that the presence of only one rib 26 would prevent this. It is also clear that the extractor may be constructed with a greater or less number of blades 29 and diagonal 30 passages 29' than here shown, or even with only one such passage. Ribs 26 and blades 29 need not necessarily correspond in number, so that there may be more or less of one than the other.

35 For supporting and rotating the extractor, the outer ring 27 of the latter is flanged outwardly at 32 to rest on rollers 33, the latter journaled in brackets 34 secured to the outer face of hopper 5. The circular toothed rack 40 35 on the outer edge of flange 32 is in mesh with the gear wheel 36 on the short vertical shaft 38 with drive shaft 39. Thus, a substantial roller support is provided for the extractor, together with simple and efficient 45 means for effecting its rotation.

In Fig. 6 the improved ash hopper and extractor are shown adapted to a blast pipe entering the lower portion of the producer instead of the upper portion, as in the preferred embodiment. For this adaptation, the cone-cap 25 of Fig. 1 is omitted and in place thereof the central passage 40 is provided through which the blast pipe 13 enters, being provided at its inner end with the 55 usual bonnet 41.

I claim:—

1. An ash extractor for gas producers consisting of a body having openings therethrough from top to bottom forming passages for the discharge of ashes from above, the passages being disposed diagonally and having inclined or sloping walls over which the ashes pass.

2. An ash extractor for gas producers consisting of a body having openings there-

through from top to bottom forming passages for the discharge of ashes from above, the passages being disposed diagonally and having inclined or sloping walls over which the ashes pass, each diagonal passage being 70 of such relative length and width that the upper or inlet end thereof and the lower or discharge end are in wholly different vertical planes.

3. An ash extractor for gas producers having a series of inclined blade-like members spaced apart to form inclined passages for the discharge of ashes from above.

4. An ash extractor for gas producers having a series of inclined blade-like members 80 spaced apart to form passages for the discharge of ashes from above, the upper portion of each blade overlapping the lower portion of the blade next adjacent to prevent movement of ashes through the extractor in 85 a vertical plane.

5. The combination of a producer body open at the bottom, an ash extractor movable horizontally beneath the open bottom, means preventing movement of ashes in the 90 body with the extractor, the extractor having diagonal openings extending from top to bottom to form inclined passages having sloping walls over which the ashes pass.

6. The combination of a producer body, 95 an ash hopper therefor having an open bottom provided with ribs and a movable ash extractor beneath the hopper, the extractor having blades spaced apart and operating with the ribs of the hopper for discharging 100 ashes.

7. The combination of a producer body, a vertically open ash hopper, radially arranged ribs within the hopper, and a rotatable ash extractor beneath the hopper and having 105 blades spaced apart which operate with the hopper ribs for discharging the ashes.

8. The combination of a producer body, an annular vertically open ash hopper having an open bottom, ribs arranged radially within the hopper and having downwardly sloping faces, and a rotatable ash extractor beneath the hopper, the extractor having a series of radially arranged inclined and laterally overlapping blades, the blades being spaced apart vertically and coöperating with the ribs of the hopper for extracting the ashes.

9. The combination of a producer body, an annular ash hopper therefor having an open bottom, radially arranged ribs secured 120 in the hopper, and a rotatable extractor beneath the hopper, the extractor having blades spaced apart and coöperating with the ribs of the hopper for removing the ashes, the lower edges of said ribs and the upper 125 edges of said blades being serrated, for the purpose described.

10. The combination of a producer body, an annular ash hopper therefor, a conical part in the center of the hopper body, ribs 130

radiating from said conical part to the shell of the hopper with vertically opening spaces between the ribs, a rotatable ash extractor beneath the hopper, the extractor having a central portion beneath the said conical part, and blades between the central part and the outer portion of the extractor, the blades being spaced apart and coöperating with the ribs of the hopper for removing the 10 ashes.

11. The combination of a producer body, an ash hopper therefor, ribs in the hopper

with vertically open spaces between the ribs, an annular support at the bottom of the hopper, an ash extractor rotatable on the support, and blades on the extractor, the blades being spaced apart and coöperating with said ribs for removing the ashes. 15

In testimony whereof I affix my signature in presence of two witnesses.

JOHN A. SMITMANS.
